(57) **CLAIM**

The ornamental design for a case for protecting a mobile device, as shown and described.

DESCRIPTION

FIG. 1 is a front view of a first embodiment of a case for protecting a mobile device showing my design, in a closed orientation;

FIG. 2 is a rear view thereof, in a closed orientation;

FIG. 3 is a left side view thereof, in a closed orientation;

FIG. 4 is a right side view thereof, in a closed orientation;

FIG. 5 is a top view thereof, in a closed orientation;

FIG. 6 is a bottom view thereof, in a closed orientation;

FIG. 7 is a front view thereof, in an open orientation;

FIG. 8 is a rear view thereof, in an open orientation;

FIG. 9 is a left side view thereof, in an open orientation;

FIG. 10 is a right side view thereof, in an open orientation;

FIG. 11 is a top view thereof, in an open orientation;

FIG. 12 is a bottom view thereof, in an open orientation;

FIG. 13 is a front perspective view thereof, in an open orientation;

FIG. 14 is a front view of a second embodiment of a case for protecting a mobile device showing my design, in a closed orientation;

FIG. 15 is a rear view thereof, in a closed orientation;

FIG. 16 is a left side view thereof, in a closed orientation;

FIG. 17 is a right side view thereof, in a closed orientation;

FIG. 18 is a top view thereof, in a closed orientation;

FIG. 19 is a bottom view thereof, in a closed orientation;

FIG. 20 is a front view thereof, in an open orientation;

FIG. 21 is a rear view thereof, in an open orientation;

FIG. 22 is a left side view thereof, in an open orientation;

FIG. 23 is a right side view thereof, in an open orientation;

FIG. 24 is a top view thereof, in an open orientation;

FIG. 25 is a bottom view thereof, in an open orientation; and,

FIG. 26 is a front perspective view thereof, in an open orientation.
